UNITED STATES PATENT OFFICE

148,576

DESIGN FOR A PHONOGRAPH CABINET

Jean O. Reinecke, Oak Park, Ill., assignor to A M I Incorporated, Chicago, Ill., a corporation of Michigan

Application July 27, 1946, Serial No. 132,018

Term of patent 7 years

(Cl. D56—4)

To all whom it may concern:

Be it known that I, Jean O. Reinecke, a citizen of the United States, residing at Oak Park, in the county of Cook and State of Illinois, have invented a new, original, and ornamental Design for Phonograph Cabinet, of which the following is a specification, reference being had to the accompanying drawing, forming a part thereof.

In the drawing:

Fig. 1 is a front elevational view of a phonograph cabinet showing my new design; and

Fig. 2 is a side elevational view thereof.

I claim:

The ornamental design for a phonograph cabinet, as shown.

JEAN O. REINECKE.
